UNITED STATES PATENT OFFICE.

FREDERICK T. THRUSH, OF MILWAUKEE, WISCONSIN.

DESIGN FOR A HEAD FOR A TOY WINDMILL.

SPECIFICATION forming part of Design No. 22,164, dated January 24, 1893.

Application filed October 8, 1892. Serial No. 448,257. Term of patent 7 years.

To all whom it may concern:

Be it known that I, FREDERICK T. THRUSH, of Milwaukee, in the county of Milwaukee and State of Wisconsin, have invented a new and useful Design for the Head of a Toy Windmill, of which the following is a description, reference being had to the accompanying drawings, which are a part of this specification.

Figure 1, of the drawings, is an elevation of my design for the head of a toy windmill, and Fig. 2, is a plan view thereof.

Like letters of reference designate like parts in both figures of the drawings.

The leading feature of my design consists in the head of a toy windmill of the form shown.

In the accompanying drawings, the letter B indicates the head of a toy windmill designed in accordance with my invention. This head consists of arms, b, b, intersecting each other

centrally. The ends of the arms are formed with wings, b' b', which extend downward at an incline. These arms are further formed with suitable surface ornamentation, consisting of contrasted colors to give an artistic effect, as clearly indicated by the shade lines on the drawings, while the wings b' are of bright colors, with fanciful pictures or images appearing thereon in contrasted colors, the whole combining to produce a new and 30 æsthetic effect.

I claim:

The design for the head of a toy windmill, substantially as herein shown and described.

In testimony whereof I affix my signature in 35 presence of two witnesses.

FREDERICK T. THRUSH.

Witnesses:

C. T. BENEDICT,
ANNA V. FAUST.
